UNITED STATES PATENT OFFICE.

WILLIAM H. JACKSON, OF LOCKPORT, NEW YORK.

WATER-BOX FOR CALENDERING-MACHINES.

1,301,703.

Specification of Letters Patent. Patented Apr. 22, 1919.

Application filed June 5, 1913. Serial No. 238,381.

To all whom it may concern:

Be it known that I, WILLIAM H. JACKSON, a citizen of the United States, and a resident of Lockport, in the county of Niagara and State of New York, have invented a new and Improved Water-Box for Calendering-Machines, of which the following is a full, clear, and exact description.

The invention relates to the manufacture of paper and its object is to provide a new and improved water box more especially designed for giving a "water finish" to the paper while the latter passes through the calendering machine, and arranged to prevent leakage of the water especially in case the calender roll should pick up foreign matter liable to lodge between the surface of the calender roll and the water supplying strip of felt. Another object is to keep the water in the supply chamber practically at a constant level with a view to insure the application of a uniform amount of water to the paper. Another object is to provide means for quickly attaching the water box to the bearings of the calender roll or removing it therefrom.

With these and other objects in view, the invention consists of certain novel features of construction, as hereinafter shown and described, and then specifically pointed out in the claims.

A practical embodiment of the invention is represented in the accompanying drawings forming a part of this specification; in which similar characters of reference indicate corresponding parts in all the views.

Figure 1 is a plan view of the water box as applied to a paper calendering machine, the standards of which are shown in section; Fig. 2 is a sectional side elevation of the same on the line 2—2 of Fig 1;

Fig. 3 is a similar view of the same on the line 3—3 of Fig. 1, and showing more particularly the fastening means for fastening the water box to the bearings of the calender roll;

Fig. 4 is a plan view of the bottom of the water box; and

Fig. 5 is an inverted plan view of the felt carrying top of the water box.

The peripheral face of the calender roll 10 of a calendering machine of usual construction is engaged by the upper end of a strip 11 of felt or other suitable fabric material disposed tangentially at one side of the roll, as plainly indicated in Fig. 2. The

strip 11 is secured to the front of the top 12 of the water box 13, and which top is provided with a water-receiving trough or chamber 14, the front end of which is formed by the upper portion of the strip 11. A water supply pipe 15 discharges into the water chamber 14 and is connected with a suitable source of water supply to keep the chamber 14 filled with water thus maintaining the water at a constant level in the chamber 14. Sufficient water is supplied by the pipe 15 to provide an overflow which flows down an inclined channel 16 formed in the top 12 of the water box.

The lower end of the strip 11 extends onto the upper surface 20 of the bottom 21 of the water box and this surface 20 is approximately parallel to the channel 16 and is inclined downwardly to carry off the water and extraneous matter flowing down the strip 11. The lower end of the surface 20 leads into a gathering channel 22 formed in the bottom 21 and provided with an outlet pipe 23 for carrying the water off to a suitable place of discharge. In order to facilitate the down flow of the water on the surface 20 the under side of the top 12 is provided with spaced channels 24 leading to the gathering channel 22, and apertures 25 are formed in the top 12 at the lower ends of the channels 24 to connect with the receiving chamber 17 thus allowing the water to flow from this chamber 17 into the gathering channel 22, from which the water can pass to a suitable place of discharge by the outlet pipe 23. The top 12 is fastened in position on the bottom 21 by screws 30 and 31 or other suitable fastening devices.

In order to support the water box 13 from the journal bearings 40 of the calender roll 10 the following arrangement is made: To the bearings 40 are secured brackets 41 each provided with an inclined guideway 42 which is narrower at the upper end than the lower end, as plainly indicated in Fig. 3. Into the guideways 42 project extensions 43 of the bottom of the water box, and wedges 44 are driven into the guideways against the extensions 43 to securely fasten the water box in position on the brackets 41. It will be noticed that when the wedges 44 are loosened the water box can be moved up or down in the guideways 42 so as to move the strip 11 in proper contact with the peripheral face of the calender roll 10, and when the desired position is reached

the water box is fastened in place by driving the wedges 44 home against the extensions 43 of the bottom 21 of the water box.

From the foregoing it will be seen that by 5 the arrangement described, the water box can be readily adjusted relative to the calender roll and leakage is prevented especially in case the calender roll picks up foreign matter liable to lodge between the 10 surface of the roll and the strip 11 of felt.

It will also be noticed that the water is 15 practically kept at a constant level in the water receiving chamber 14 to insure a uniform application of water to the paper passing over the calender roll. It will also be 20 noticed that the water box can be readily detached from the calendering machine, but when in position it moves up and down with a possible up and down movement of the calender roll.

Having thus described my invention, I claim as new and desire to secure by Letters Patent:

1. In a water box for a calender roll, an 25 inclined strip of fabric material in tangential position relative to the peripheral face of the calender roll and in contact at its upper end with the peripheral face of the calender roll, and an inclined surface abutting 30 the lower end of the said strip for carrying off water passing down the said strip.

2. In a water box for a calender roll, an 35 inclined strip of fabric material in tangential position relative to the peripheral face of the calender roll and having the under side of its upper end in contact with the said calender roll, a water supply chamber having its forward end formed by the said strip,

and a water carrying off surface onto which projects the lower end of the said strip 40 for carrying off the water passing down the strip.

3. In a water box for a calender roll, an inclined strip of fabric material in tangential position relative to the peripheral face 45 of the calender roll and having the under side of its upper end in contact with the said calender roll, a water supply chamber having its forward end formed by the said strip, a water carrying off surface onto 50 which projects the lower end of the said strip for carrying off the water passing down the strip, an overflow chamber receiving the overflow water from the said supply chamber, and a draining chamber receiving 55 the water from the said surface and the said overflow.

4. In combination, a calender roll, bearings in which the said roll is journaled, brackets attached to the bearings, and a 60 water box adjustably secured to the said brackets.

5. In combination, a calender roll, bearings in which the said roll is journaled, brackets attached to the bearings and provided with tapering guideways, a water box 65 having members extending into the said guideways, the water box having a strip of felt in contact with the said roll, and wedges driven in the guideways against the said box 70 members to adjustably and detachably fasten the water box in place.

WILLIAM H. JACKSON.
